DETROIT FUSE & MFG. COMPANY, OF DETROIT, MICHIGAN, A CORPORATION
OF MICHIGAN.

ELECTRICAL SWITCH.

1,383,808.

Specification of Letters Patent.

Patented July 5, 1921.

Application filed March 4, 1916. Serial No. 82,197.

To all whom it may concern:

Be it known that we, BRYSON DEXTER HORTON and ALBERT P. BALL, citizens of the United States, residing at Detroit, county of Wayne, State of Michigan, and Royal Oak, Oakland county, State of Michigan, respectively, and FREDERICK ZENKER, a subject of the Emperor of Germany, residing at Highland Park, county of Wayne, and State of Michigan, have invented certain new and useful Improvements in Electrical Switches, of which the following, taken in connection with the accompanying sheet of drawings, is a full, clear, and concise description thereof, 15 such as will enable others skilled in the art to make and use the same.

Our present invention relates to electrical switches used for starting electric motors. Among the objects of our invention is the provision of a double throw switch in which the movable contacts cannot be thrown to running position without having first been moved to starting position. Another object is to provide an arrangement which will insure the rapid operation of the movable contacts from starting to running positions.

Other objects of our invention will manifest themselves upon a reading of the following specification:

Referring to the accompanying drawings, in which we have illustrated, by way of example only, one preferred embodiment of our invention, and in which like reference numerals represent like parts throughout the 35 respective views, we will proceed to describe the same in detail.

Figure 1 is a view in top plan of a double-throw motor starting switch, the same being held in neutral or "off" position, by controlling mechanism which forms one of the important features of our present invention.

Fig. 2 is an enlarged fragmentary detail illustrating the controlling means in released position, the operating switch crank about 45 to close the circuit between the movable and stationary service contacts.

Fig. 2^a is an enlarged detail of the form of connector employed to connect the movable knife-blade contacts with the operating 50 crank of the switch in the embodiment illustrated in Figs. 1 and 2.

Fig. 3 is an enlarged detail of a modified

form of connector employed to connect the movable blade contacts with the operating crank of the switch.

55

The switch mechanism is housed within a sheet metal protecting housing, 1 which is provided with a hinged cover 2. The ends of this housing are apertured, said apertures being covered by removable end plates 3, which may be provided with conveniently-arranged knock-outs (not shown) for the accommodation of the entrance and exit conductors. These end plates 3 are held in place by inturned ears 4, stamped from the sides of the housing and screws 5, the latter also serving to form a positive ground for the removable plates 3. Mounted within the casing and upon the bottom thereof is the insulating base 6, carrying the switch 70 parts. These switch parts comprise the stationary running contacts 7, fuse holders 8, which accommodate the running fuses indicated at 8', starter contacts 9 and the stationary supports 10 which serve as pivot supports for the movable knife-blade contacts 11, pivotally mounted thereon at 12, and also as conductor-carrying parts for the current passing through the motor wires or conductors 13. Extending laterally across the housing and having bearings in the sides thereof is the operating crank 14.

75

This operating-crank is preferably made of one piece of metal bent to form and has operable connection with the movable knife-blade contacts 11 through the insulating sleeves 15, and connecting devices 16, the latter being preferably made of two parts 17 and 18 held together by suitable screws 19 at one end, the opposite end of part 18 being provided with an interlocking connection as at 20 with the part 17. In the modified form of connection shown in Fig. 3 the part 18 may, instead of consisting of a flat metal strip, comprise a wire 21, one end being formed into an eye 22, which encircles the screw 19 beneath the head thereof, the opposite end being inserted through an aperture 23 and bent over as at 24. The part 17

80

is provided with an aperture 18' to accommodate a connecting screw which fastens it to the knife-blade contact 11.

85

Fig. 2^a is an enlarged detail of the form of connector employed to connect the movable knife-blade contacts with the operating 90 crank of the switch in the embodiment illustrated in Figs. 1 and 2.

95

It will be understood that the crank 14 is capable of assuming two positions, one

ward said running contacts without first engaging said starting contacts.

3. In an electrical switch of the character described, the combination with stationary starting contacts, of stationary running contacts, movable contacts, means for obstructing the path of movement of said movable contacts when moving from one set of said stationary contacts to another, and for locking such movable contacts in neutral position, and spring means for snapping said obstructing means into locking engagement with said movable contacts unless moved past said obstructing means with great rapidity, said spring means positioning said obstructing means in operative position and permitting its deflection in either direction.

4. A connection for connecting movable contacts with an operating crank, comprising a member adapted to be connected with the movable contact provided with a laterally-extending flanged portion, and a coöperating member adapted to encircle the crank, one end of the latter member having interlocking connection with said first member, and the other end having screw connection therewith.

5. In combination with an oscillatory switch member, a hinged plate provided with a recess arranged to coöperate with said switch member, said plate being adapted to confine said switch member when the same is in neutral or "off" position and prevent its being moved in one direction, while permitting its movement in the opposite direction, spring means bearing upon the plate and urging it into position to coöperate with the switch member when the latter is in neutral or "off" position, said spring means permitting the deflection of said plate in either direction.

6. The combination with a pivotally mounted switch crank, of a substantially flat plate pivotally mounted in proximity thereto, the plate being provided with a recessed portion, one side of said recess comprising a cam which is integral with the plate and bent out of the plane of the plate, said plate coöperating with the crank when at rest in the recess to permit the crank to be moved only past the cam whereby the plate is deflected on its pivotal mounting, and spring means to return the plate to normal position after the crank has so deflected it.

55 7. The combination with a pivotally mounted switch crank, of a substantially flat rectangular plate pivotally mounted in proximity thereto, the plate being provided with a recessed portion along one edge, one corner of said plate being bent laterally to facilitate deflection of the plate when it is engaged by the crank to permit the latter to enter the recess, and spring means urging the plate to its normal position.

65 8. In a motor starter switch, the combina-

tion with the wall of a housing, of two series of stationary contacts, a series of pivotally mounted movable contacts for coöperating with said stationary contacts, a coöperating movable crank operably connected to said movable contacts for actuating the same to travel from one set of stationary contacts to the other, a portion of said crank traveling in a path of movement parallel to said wall, an anchoring plate hingedly connected to said wall, and means for positioning said plate at right angles to said wall and in the path of movement of said crank portion when actuating said movable contacts to travel from one set of stationary contacts to the other, there being a recess in said plate for receiving said crank portion and locking the same and the thereto connected movable contacts in neutral position.

9. In a motor starter switch, the combination with the wall of a housing, of two series of stationary contacts, a series of pivotally mounted movable contacts for coöperating with said stationary contacts, a coöperating crank operably connected to said movable contacts for actuating the same to travel from one set of stationary contacts to the other, a portion of said crank traveling in a path of movement parallel to said wall, an anchoring plate hingedly connected to said wall, means for positioning said plate at right angles to said wall and in the path of movement of said crank portion when actuating said movable contacts to travel from one set of stationary contacts to the other, means on said plate for anchoring said crank portion and the thereto connected movable contacts in neutral position, and means for preventing removal of said crank portion from engagement with said plate in one direction but facilitating the removal thereof in the other direction.

10. In a motor starter switch, the combination with the wall of a housing, of two series of stationary contacts, a series of pivotally mounted movable contacts for coöperating with said stationary contacts, a coöperating crank operably connected to said movable contacts for actuating the same to travel from one set of stationary contacts to the other, a portion of said crank traveling in a path of movement parallel to said wall, an anchoring plate hingedly connected to said wall, and means for resiliently positioning said plate at right angles to said wall and in the path of movement of said crank portion when actuating said movable contacts to travel from one set of stationary contacts to the other, there being a recess in said plate for receiving said crank portion and locking the same and the thereto connected movable contacts in neutral position, a portion of said plate adjacent to one side of said recess serving to prevent the removal of said crank portion from said recess when urged

in one direction, and a portion of said plate adjacent to the other side of said recess constituting a cam to facilitate the removal of said crank portion when urged in the other 5 direction.

11. In a motor starter switch, the combination with the wall of a housing, of stationary running contacts, stationary starting contacts, a series of pivotally mounted movable contacts for alternately coöperating with said stationary contacts, a coöperating crank operably connected to said movable contacts for actuating the same to travel from one 10 set of stationary contacts to the other, a portion of said crank traveling in a path of movement parallel to said wall, an anchoring plate hingedly connected to said wall, means for resiliently positioning said plate at right angles to said wall and 15 in the path of movement of said crank portion when actuating said movable contacts to travel from one set of stationary contacts to the other, there being a recess in said plate for receiving said crank portion and locking the same and the thereto 20 connected movable contacts in neutral position, a portion of said plate adjacent to one side of said recess serving to prevent the removal of said crank portion from 25 said recess when urged in one direction, and a portion of said plate adjacent to the other side of said recess constituting a cam to facilitate the removal of said crank portion when urged in the other direction, 30 and another portion of said plate being bent laterally to facilitate the oscillation of said plate when said crank portion is moved from the running position to the neutral position.

12. In a motor starter switch, the combination with the wall of a housing, of stationary running contacts, stationary starting contacts, a series of pivotally mounted movable contacts for alternately coöperating with said stationary contacts, a coöperating 40 crank operably connected to said movable contacts for actuating the same to travel from one set of stationary contacts to the other, a portion of said crank traveling in a path of movement parallel to said wall, an anchoring plate hingedly connected to said wall, means for resiliently positioning said plate at right angles to said wall and 45 in the path of movement of said crank portion when actuating said movable contacts to travel from one set of stationary contacts to the other, there being a recess in said plate for receiving said crank portion and locking the same and the thereto 50 connected movable contacts in neutral position, a portion of said plate adjacent to one side of said recess serving to prevent the removal of said crank portion from said recess when urged in one direction, and a portion of said plate 55 adjacent to the other side of said recess constituting a cam to facilitate the removal of said 60 plate.

13. In a motor starting switch having stationary starting and running contact mem-

said crank portion when urged in the other direction, the cam also engaging the crank to oscillate the same to permit the crank portion to be moved rapidly past the recess in the first direction.

14. In a motor starter switch, the combination with the wall of a housing, of two series of stationary contacts, a series of pivotally mounted movable contacts for coöperating with said stationary contacts, a coöperating crank operably connected to said movable contacts for actuating the same to travel from one set of stationary contacts to the other, a portion of said crank traveling in a path of movement parallel to said wall, an anchoring plate hingedly connected to said wall, means on said plate for anchoring said crank portion and the thereto connected movable contacts in neutral position, an arcuate rod extending through said plate connected to said wall at one end and having a stop at its other end, and spring means between said plate and said stop and wall to normally maintain said plate in extended position and in the path of movement of said crank portion.

15. In a motor starter switch, the combination with a housing, two series of stationary contacts, a series of pivotally mounted movable contacts for coöperating with either series of stationary contacts, an operating crank independently pivoted in the walls of the housing for moving said movable contacts, internal means for allowing said operating crank to move said movable contacts only in one definite order, said internal means directly engaging said operating crank.

16. A motor starter having stationary starting contact members, stationary running contact members and movable contact members coöperative therewith, means for operating said movable contact members in unison, means for controlling the sequence of operation of the movable contact members, means urging the movable contacts toward the running contacts, and means comprising a casing with a cover for inclosing the aforesaid, the positioning of the movable contact members and operation of the sequence controlling means being independent of the cover, whose removal affords access to all the inclosed parts.

17. In a motor starting switch having stationary starting and running contact members, and coöperative movable contact members, the combination of means controlling the sequence of operations of said switch and allowing only a rapid motion of the movable contact members from starting to running position, and automatic means for quickly throwing said switch from starting to running position.

18. In a motor starting switch having stationary starting and running contact mem-

- bers and coöperative movable contact members, the combination of means controlling the sequence of operations of said switch and allowing only a rapid motion of the movable contact members from starting to running position, comprising a one-piece spring tensioned member, and automatic means for quickly throwing said switch from starting to running position.
- 10 18. In a motor starting switch having stationary starting and running contact members and coöperative movable contact members, and a cross head connecting said movable contact members, the combination of means controlling the sequence of operations of said switch, comprising a member directly engaging said cross head and allowing only a rapid motion of the movable contact members from starting to running position, and automatic means for throwing said switch from starting to running position.
- 15 means controlling the sequence of operations of said switch, comprising a member directly engaging said cross head and automatic
- means for throwing said switch from starting to running position.
19. In a motor starting switch having stationary starting and running contact members and coöperative movable contact members and a cross head connecting said movable members, the combination of means controlling the sequence of operations of said switch, comprising a member directly engaging said cross head and allowing only a rapid motion of the movable contact members from starting to running position, and automatic means for throwing said switch from starting to running position.
